UNITED STATES PATENT OFFICE.

FLORENT HINNEKENS, OF PATERSON, NEW JERSEY.

FABRIC-SPREADING APPARATUS.

Application filed August 21, 1926. Serial No. 130,629.

The present invention relates to apparatus whereby a strip of fabric is transversely varied in extent, as stretched transversely. The stretching instrumentality employed in such apparatus comprises a body in the form of a cylinder or roll, each end portion of which includes a group of longitudinally and individually movable slats or portions, and internal cams with which 5 said slats or portions in the two groups are respectively engaged, the same being stationary but said body being revoluble about them, to the end that when the fabric is advanced in frictional gripping relation to 10 said slats or portions in the two groups are 15 and partial peripheral contact with said body and hence the latter is rotated the slats will move back and forth, i. e., each pair of alined slats (one in each group) will move alternately apart and toward each other in 20 each revolution of said body, obviously resulting in a stretching of the fabric if the cams are so rotatively positioned that the oppositely related slats which are in actual contact therewith are at that time under- 25 going the separating part of their movement. Usually a single stretching action imparted by this device is not sufficient, and so it is customary to run the strip backward and then to run it forward again subject to the 30 action of this device, repeating these operations until the desired stretch is attained: there is the objection that the backward runs are idle operations because then the oppositely related slats which are in contact with 35 the goods are at that time undergoing that part of the rotary movement in which they move together. Now it is the principal object of this invention to construct the device so that the revolving body will function to 40 stretch the goods when it is rotated in either direction, thus to avoid idle passes or runs of the fabric in one direction and produce stretching when the fabric is advanced in either direction. This I accomplish by pro- 45 viding for automatic reversal of the cams, to wit, by arranging them so that when, following a run of the fabric in one direction, the fabric is advanced in the opposite direction they will be rotated a limited dis- 50 tance (sufficient to reverse them) and hence set to the position for again causing the alined slats in the two groups which are in actual contact with the fabric to move apart for stretching.

55 In the drawings,

Fig. 1 shows the improved device em-

bodied in a machine in which the fabric may be run back and forth—here a fabric rubbing machine, though that is not material;

60 Fig. 2 is a plan of a part of what appears in Fig. 1;

Fig. 3 is a view mainly in longitudinal section of the revolving stretching body or roll, the cam-including structure and one of 65 the latter's bearing-supports;

Figs. 4 and 5 are sections on lines 4—4 and 5—5, Fig. 3; and Fig. 6 shows the sleeve of the aforesaid revolving body or stretching 70 roll.

Said revolving body or roll may have the same construction as those now in use, to wit: A sleeve or core 1 has around it a shell whose intermediate part is composed of longitudinal slats 2 (Fig. 2) riveted or otherwise fixed to it and each of whose terminal parts is composed of longitudinal slats 3 capable of movement back and forth lengthwise of the core 1, they being for that purpose provided with inwardly projecting 75 studs 4 which have spaced flanges or heads 5 and slide in slots 6 in the core or shell with the spaced flanges receiving the edges of the slots between them; the slots have key-hole shape (Fig. 6) to permit assembling 80 of the thus double-headed studs therewith. This specific construction of the body or roll is not of course material: it is only material that the body or roll shall be capable of being revolved by a moving fabric (as A) 85 held in partial peripheral contact therewith (as in drawing and hence unwinding the fabric from the roll B thereof in Fig. 1 or winding it up to form such roll) and that as to at least one end or other part of the 90 body or roll its periphery shall be composed of slats or portions (as those at one end) which are individually movable lengthwise of said body or roll toward and from another part of the latter (as the slats or 95 portions at the other end) in order to produce stretching of the fabric.

100 This body or roll is revoluble concentrically with respect to a cam structure here including a shaft 7 extending through said body or roll and cams 8 within the latter fixed (as pinned) to the shaft. Each cam has a continuous peripheral groove or cam-way 8^a pitched as to the two halves thereof 105 in opposite directions; the two cams are 110 arranged on the shaft so that the two innermost portions and two outermost portions

of their camways are respectively opposite each other, or so that for one-half of the circumference the camways converge and for the other one-half they diverge. The 5 camways receive the studs 4 of the slats 3. Anti-friction bearings 9, in bushings 10 secured in the ends of sleeve or core 1, may support the body or roll actually on the cam structure 7—8.

10 As to the operation of the mechanism so far described: Assuming the cam structure to be supported as shown for example in Figs. 1 and 2 and the body or roll to be revolved by a fabric A moving in contact therewith, if the cam structure be held against rotation and if the camways be so positioned that their diverging portions are operative on those slats 3 with which the fabric happens to be in contact said slats 15 will in consequently moving apart stretch the fabric transversely.

Heretofore, as stated, whenever more than one stretching was required this could not be accomplished in a return or backward run 20 of the fabric because then the working portions of the camways would be convergently instead of divergently related. Therefore, according to my invention the cam structure is revoluble a limited extent (half a 25 revolution) in its supporting means so as to reverse itself, that is, so that when the fabric is started on a reverse run the cam structure will take the position where the halves of its camways which were convergent with relation to and hence caused the rotating series of slats to move together in their previous direction of rotation will now be divergent with respect to the new or opposite direction of rotation of the series 30 of slats. To this end the brackets 11 are formed with housings 12 which contain anti-friction bearings 13 for the ends of the shaft 7; these housings may have inside covers 14 bolted thereto and penetrated by the 35 shaft. The shaft has a collar 15 fixed thereto and formed with a stop or projection 16. The housing is formed inside with two stops 17 so positioned that stop 16 engaged one or the other of them on turning the shaft 40 a half-revolution.

Thus, following a run of the fabric in one direction and at the inception of a reverse run the cam structure is turned in its bearings by the drag of the body or roll acting 45 thereon (to wit, by the engagement of its studs 4 in the camways), being checked by the stops when a half-revolution is completed or the cams reversed, so that those halves of the cams previously acting to move the slats together will now be acting to move 50 the slats apart, and since the slats so affected are those actually engaged by the fabric the latter will be transversely stretched.

The housings 12 not only serve to contain lubricant but as safety guards for the parts 65 they enclose.

I do not wish to be limited to the cams being revoluble concentrically with respect to the roll or body, or in fact to their being revoluble at all: it is sufficient that each cam, 70 having a camway formed with two portions of substantially equal length and oppositely oblique to the axis of revolution of said body or roll, is shiftable back and forth, revolubly or otherwise, by and with said body or roll 75 and that there be means (as stops 17) to limit the shifting of the cams one way or the other a distance equal to the length of each such oblique camway portion.

Having thus fully described my invention 80 what I claim and desire to secure by Letters Patent is:

1. In combination, supporting means, means to change the width of a fabric including a body revoluble in each direction 85 on an axis extending therethrough and adapted to be revolved by the fabric when the latter is advanced in one direction or the other in peripheral contact therewith and having the fabric-engaged periphery of a 90 part thereof composed of portions movable individually lengthwise of said axis relatively to the fabric-engaged periphery of another part of said body, and a cam structure having a camway formed with two portions of substantially equal length and oppositely oblique to said axis and arranged 95 to be engaged by said portions of said body when rotating, said cam structure being shiftable by and with said body as the latter 100 rotates one way or the other, and the supporting means having means to limit the shifting of the cam structure one way or the other a distance substantially equal to the length of one of its said camway portions. 105

2. That specific embodiment of the combination set forth in claim 1 in which the cam structure is shiftable around the axis of rotation of said body or roll.

3. That specific embodiment of the combination set forth in claim 1 in which the supporting means includes a housing containing the means to limit the shifting of the cam structure one way or the other. 110

4. That specific embodiment of the combination set forth in claim 1 in which the cam structure is shiftable around the axis of rotation of said body or roll and in which the supporting means includes a housing in which the cam structure is journaled 115 and containing the means to limit the shifting of the cam structure one way or the other. 120

In testimony whereof I affix my signature.

FLORENT HINNEKENS.
